(57) **CLAIM**

The ornamental design for a compact alignment tool for electrical device, as shown and described herein.

DESCRIPTION

FIG. 1 is a perspective view of a compact alignment tool for electrical devices, according to the new design.

FIG. 2 is a front view of the design of FIG. 1.

FIG. 3 is a right view of the design of FIG. 1.

FIG. 4 is a left view of the design of FIG. 1.

FIG. 5 is a rear view of the design of FIG. 1; and, FIG. 6 is a top view of the design of FIG. 1.

1 Claim, 4 Drawing Sheets

FIG. 1

FIG. 2

FIG. 3

FIG. 4

FIG. 5

FIG. 6
